UNITED STATES PATENT OFFICE.

AUGUSTUS B. ELLISON, OF ST. LOUIS, MISSOURI.

DESIGN FOR A BADGE.

SPECIFICATION forming part of Design No. 25,752, dated July 7, 1896.

Application filed April 4, 1896. Serial No. 586,264. Term of patent 31 years.

To all whom it may concern:

Be it known that I, AUGUSTUS B. ELLISON, of the city of St. Louis, State of Missouri, have invented a new and original Design for a Badge, of which the following is a full, clear, and exact description, reference being had to the accompanying drawings, forming a part hereof.

In the drawings, Figure 1 is a front elevation of a badge, showing my design. Fig. 2 is a horizontal sectional view taken approximately on the line 2 2 of Fig. 1.

The leading feature of my design consists in a circular body bounded by a raised border, on which body appears a raised shield-shaped figure, and upon which shield-shaped figure and circular body there appears a segmental raised band or body.

1 indicates the body of the badge, which is in the form of a convex-faced disk bounded by the circular border 2. Appearing upon the face of the body 1 is the raised shield-shaped figure 3, the upper portion 4 of the

face of which figure is left plain in order to receive suitable lettering. Extending diagonally across the faces of the shield-shaped figure 3 and the disk 1 is a curved raised band or body 5, the edges of which are bordered by the raised portions 6. The face 7 of this band or body is formed plain to receive suitable marking. Formed integral with and extending rearwardly from the body 1 is a body 8, on the end of which is formed integral a circular body 9, the outer edge 10 of which is turned inwardly toward the body 1 and notched or serrated, as indicated by 11.

I claim—

The design for a badge substantially as herein shown and described.

In testimony whereof I affix my signature in presence of two witnesses.

AUGUSTUS B. ELLISON.

Witnesses:

DAVID O. MILLS,
J. A. HINSON.
